AUTOMATIC STOP FOR SEWING MACHINES

Martin S. Mansson, Long Island City, N. Y.

Application October 6, 1949, Serial No. 119,980

12 Claims. (Cl. 200—52)

1

The present invention is directed to circuit closing devices of sensitive nature, more particularly to a device of this kind adapted for breaking the circuit of a sewing machine motor in order to stop the operation thereof.

In modern high-speed sewing machines, it is necessary to provide safeguards so that when there is an accidental defect in the operation, the machine may be stopped at the earliest possible moment. For instance, it often happens that in the operation of the sewing machine, an irregularity occurs whereby the thread may skip a stitch. This, of course, is undesirable and the machine should be stopped when this occurs in order to adjust the same properly. However, in the past, no satisfactory device for stopping a machine under these circumstances has been on the market.

It also happens quite frequently that a bobbin thread runs out and it may be some time before the operator notices it so that a defective piece of stitching results. The same occurs when the bobbin thread breaks as the operator, not being in a position to notice the running out or breaking of the thread, will not become aware of it until considerable damage has been done.

The present invention is intended and adapted to overcome the difficulties and disadvantages of the prior art, it being among the objects of the invention to provide a simple, compact and sensitive arrangement which will stop the motor of a sewing machine when a bobbin thread runs out or when a thread skips a stitch.

It is also among the objects of the present invention to provide an arrangement which may be attached to the head of a sewing machine and which is operated by the thread passing through the sewing machine needle.

It is further among the objects of the present invention to provide a switching arrangement of the type described, which is compact and which is adapted for various uses where a current is to be made or broken under special conditions.

In practicing the invention, and particularly in connection with a sewing machine, there is provided a pressure sensitive member which may be in the form of a wire placed in a position in back of and adjacent to the needle and the thread passing therethrough. When the sewing machine is operating normally, the thread does not contact the pressure sensitive member but when the machine skips a stitch, the thread is pulled in the direction of the member and in making contact therewith, operates the mechanism which eventually opens the motor circuit and stops the machine. Similarly, when the bobbin thread runs out or breaks, the needle thread is pulled in the direction of the sensitive

2

member and operates the switch mechanism to stop the motor.

There is provided a receptacle with a shaft pivoted on one of its walls and the pressure sensitive member is secured to the shaft on the outside of the receptacle. The shaft also has an extension within the receptacle, said extension having an open end in the nature of a slot or a slit. In proximity to said slot is a stub shaft which is also pivoted in the receptacle and this has a movable contact member secured thereto. The contact member lies close to and approximately parallel with the extension.

A projection on the movable contact member and adjacent to the stub shaft has its end inserted into the slot of the extension. Thereby upon the movement of the pressure sensitive member, this shaft oscillates, causing the extension to move the projection and thus cause the movable contact to engage with or disengage from a fixed contact which is also mounted in the receptacle. A single wire is usually electrically secured to the fixed contact to form part of the circuit and a second wire is dispensed with as the metal members complete the circuit. Usually a cover, transparent in character, closes the open face of the receptacle.

In the accompanying drawing constituting a part hereof and in which like reference characters indicate like parts,

Fig. 1 is a front elevational view of a device made in accordance with the present invention and shown as attached to the head of a sewing machine;

Fig. 2 is a side elevational view thereof;

Fig. 3 is a view similar to Fig. 1, showing a modified form of the arrangement of elements within the receptacle;

Fig. 4 is a vertical cross-sectional view through the housing, and

Figs. 5 and 6 are side and front views of a modification.

The arm 1 of a sewing machine has the usual sewing head 2 containing the sewing instrumentalities including a presser foot bar and a needle bar. The sensitive arrangement is secured to a stationary part of head 2 and includes a receptacle having an annular housing 3 having a disk-like base 4 with a cover plate 5 of insulating material. The cover is secured to the base by set screws 6.

A shaft 7 passing through base 4 is covered by cap 8 secured thereto by set screw 9. A wire 10 passing through an opening in cap 8 is held in adjusted position by set screw 11. The lower end 12 is in the form of a horizontal bar in proximity to the needle. On shaft 7 within the receptacle is an extension 13 fixed to the shaft and having at its left hand end a slit or slot or opening 14.

Just beyond slot 14 is a stub shaft 15 having the base 16 of a contact member 17 fixed thereon. A projection 18 extends into slot 14. Contact 19 is secured to 17 near its outer end. As shown in Fig. 1, contact member 17 is substantially parallel to and overlies extension 13, thus providing a very compact arrangement. Because of the several lever arms involved, a very slight movement of wire 10 will cause a positive movement of movable contact 19.

Within the receptacle and just above stub shaft 15 is plate 20 having a slot 21 therein, held to base 4 by suitable means such as a set screw. A hairspring 22 has one end secured in plate 20 and is looped in the form of an arc with its end 23 in the form of a reverse curve or V in contact with the end of contact member 17. The spring has the function of retaining the contact positively in both open and closed positions. Because of the screw and slot arrangement, the position and tension of hairspring 22 may be adjusted.

A stationary contact 24 just above movable contact 19 is held on member 25 secured to cover plate 5 by a screw 26. A cap 27 is adapted to frictionally engage the outer end of screw 26 and carries a wire for making an electrical connection to the fixed contact. The movable contact 19 has no wire associated with it but is grounded on the metal parts of the machine itself.

To the outer surface of base 4 is secured a bevelled flat plate 28 and an angular member 29 is secured to plate 28 by screws 30. The other angle of said plate constitutes a finger 31 for contacting with the presser foot bar. Angular member 29 is adapted to slide in a groove 32 of block 33. Around screw 34 on block 33 is secured one end of a wire spring 35 which passes around screw 36 and the other end 37 rests upon pin 38 in the front of tongue 28. The tension of the spring is such as to tend to force tongue 28 downwardly. A pin 39 on the back of tongue 28 is adapted to contact the body of block 33 to act as a stop, limiting the downward movement of 28.

At the rear of block 33 is a complementary block or clamp 40 secured to block 33 by screws 41. At the junction of 33 and 40 are a pair of recesses or openings 42 partially in each of the members.

Extending downwardly from head 2 are needle bar 43 and presser foot bar 44. Needle 45 extends from the lower end of needle bar 43 and is slightly in front of bar 12 of the sensitive wire 10. Extending downwardly from presser foot bar 44 is presser foot 46 in its usual relationship to the needle 45. The upper part 47 of the presser foot is adapted to engage finger 31 so that when the presser foot is lifted, finger 31 is lifted simultaneously and this raises receptacle 3 up with it, thus allowing full access to the fabric being sewn.

In the operation of the device during the normal use of the sewing machine, the elements are in the positions shown in Fig. 1 with the thread 48 extending substantially vertically downward from the eye of the needle and into the fabric being operated on. The several elements of the switching arrangement are also in the position shown in Fig. 1, with movable contact 19 spaced from stationary contact 24. If the bobbin thread should run out or break, thread 48 moves rearwardly, taking the position 49, as shown in Fig. 1, contacting with bar 12 of wire 10. This causes a movement to the rear of wire 10, causing extensions 13 to pivot upwardly on shaft 7. This

in turn causes projection 18 to be raised, rotating stub shaft 15 and raising contact member 17. The force is sufficient to cause the end of said contact member to rise past the V-shaped portion 23 of hairspring 22, thus closing the circuit. Current passing through the circuit may be utilized to operate a relay which in turn opens the motor circuit of the sewing machine and thus stops the operation thereof.

10 In the modification shown in Fig. 3, in place of extension 13 which is in the form of a flat bar, there may be provided a U-shaped member 49, the central part of which embraces shaft 7 and is fixed thereto as by soldering. The ends of the legs of the U define a slot or opening 50 into which projection 18 extends. The several elements are shown in the position they assume when the switch circuit is closed and the motor is stopped.

15 In Figs. 5 and 6 is shown a clamp 51 held on bushing 52 by screws 53. A bracket 54, integral with the clamp, extends rearwardly and an arm 55 is pivoted thereto by pin 56. Plate 57 fixed on the free end of arm 55 has a projecting lug 58 adapted to contact the top 59 of the presser foot. Projection 60 on bracket 54 limits the downward movement of the arm and spring 61 tends to maintain the arm in the position shown.

20 Although the invention has been described setting forth several specific embodiments thereof, various changes in the details of the construction may be made without departing from the principles herein set forth. For instance, cover 5 of insulating material is sometimes made transparent but it may be opaque, if desired. Receptacle 3 is illustrated as being circular in shape but various other shapes may be substituted for it. The relative positions of the parts within the receptacle may be considerably altered while retaining the compact arrangement, all within the scope of the invention. The means for mounting the pressure sensitive device may be different from that shown and, for instance, block 33 may be directly secured to head 2 without the necessity of a clamping arrangement. The device itself apart from the mounting means may be used in various applications where a pressure sensitive means for opening and closing a circuit is desired.

25 These and other changes may be made within the spirit of the invention, which is to be broadly construed and not to be limited except by the character of the claims appended hereto.

30 I claim:

1. A sensitive mechanism for controlling an electrical circuit such as that of a sewing machine motor comprising a receptacle, a shaft pivoted within and on a wall thereof and having a pressure sensitive member secured thereon on the outside of said receptacle and adapted to contact with a thread under tension and to be moved thereby, an extension on said shaft in said receptacle, a stub shaft pivoted in said receptacle in proximity to the free end of said extension, a movable contact member secured to said stub, a projection on said movable contact cooperatively attached to the end of said extension, whereby oscillation of said shaft causes oscillation of said stub shaft and movable contact, a fixed contact in proximity to said movable contact and adapted to close a circuit therewith, and a spring one end of which is attached to said receptacle and the other end having an angular portion in said receptacle engaging the free end

of said movable contact to maintain it in open and closed positions alternately.

2. A sensitive mechanism for controlling an electrical circuit such as that of a sewing machine motor comprising a receptacle, a shaft pivoted within and on a wall thereof and having a pressure sensitive member secured thereon on the outside of said receptacle and adapted to contact with a thread under tension and to be moved thereby, an extension on said shaft in said receptacle, a stub shaft pivoted in said receptacle in proximity to the free end of said extension, a movable contact member secured to said stub, a projection on said movable contact cooperatively attached to the end of said extension, whereby oscillation of said shaft causes oscillation of said stub shaft and movable contact, a fixed contact in proximity to said movable contact and adapted to close a circuit therewith, said movable contact overlying said extension, and a spring one end of which is attached to said receptacle and the other end having an angular portion in said receptacle engaging the free end of said movable contact to maintain it in open and closed positions alternately.

3. A sensitive mechanism for controlling an electrical circuit such as that of a sewing machine motor comprising a receptacle, a shaft pivoted within and on a wall thereof and having a pressure sensitive member secured thereon on the outside of said receptacle and adapted to contact with a thread under tension and to be moved thereby, an extension on said shaft in said receptacle, a stub shaft pivoted in said receptacle in proximity to the free end of said extension, a movable contact member secured to said stub, a projection on said movable contact cooperatively attached to the end of said extension, whereby oscillation of said shaft causes oscillation of said stub shaft and movable contact, a fixed contact in proximity to said movable contact and adapted to close a circuit therewith, said movable contact overlying said extension and said fixed contact overlying said movable contact, and a spring one end of which is attached to said receptacle and the other end having an angular portion in said receptacle engaging the free end of said movable contact to maintain it in open and closed positions alternately.

4. A sensitive mechanism for controlling an electrical circuit such as that of a sewing machine motor comprising a receptacle, a shaft pivoted within and on a wall thereof and having a pressure sensitive member secured thereon on the outside of said receptacle and adapted to contact with a thread under tension and to be moved thereby, an extension on said shaft in said receptacle, a stub shaft pivoted in said receptacle in proximity to the free end of said extension, a movable contact member secured to said stub, a projection on said movable contact cooperatively attached to the end of said extension, whereby oscillation of said shaft causes oscillation of said stub shaft and movable contact, a fixed contact in proximity to said movable contact and adapted to close a circuit therewith, and a spring one end of which is attached to said receptacle, the free end of said spring in said receptacle engaging the free end of said movable contact to maintain it in open and closed positions alternately, said spring being a hair spring having an angular portion engaging the free end of said movable contact.

5. A sensitive mechanism for controlling an electrical circuit such as that of a sewing ma-

chine motor comprising a receptacle, a shaft pivoted within and on a wall thereof and having a pressure sensitive member secured thereon on the outside of said receptacle and adapted to contact with a thread under tension and to be moved thereby, an extension on said shaft in said receptacle, a stub shaft pivoted in said receptacle in proximity to the free end of said extension, a movable contact member secured to said stub, a projection on said movable contact cooperatively attached to the end of said extension, whereby oscillation of said shaft causes oscillation of said stub shaft and movable contact, a fixed contact in proximity to said movable contact and adapted to close a circuit therewith, and a spring one end of which is attached to said receptacle, the free end of said spring in said receptacle engaging the free end of said movable contact to maintain it in open and closed positions alternately, said spring being a hair spring having an angular portion engaging the free end of said movable contact with means for adjusting the position of said spring to vary the tension thereof.

6. A sensitive mechanism for controlling an electrical circuit such as that of a sewing machine motor comprising a receptacle, a shaft pivoted within and on a wall thereof and having a pressure sensitive member secured thereon on the outside of said receptacle and adapted to contact with a thread under tension and to be moved thereby, an extension on said shaft in said receptacle, a stub shaft pivoted in said receptacle in proximity to the free end of said extension, a movable contact member secured to said stub, a projection on said movable contact cooperatively attached to the end of said extension, whereby oscillation of said shaft causes oscillation of said stub shaft and movable contact, a fixed contact in proximity to said movable contact and adapted to close a circuit therewith, and a spring one end of which is attached to said receptacle, the free end of said spring in said receptacle engaging the free end of said movable contact to maintain it in open and closed positions alternately, said spring being a hair spring having an angular portion engaging the free end of said movable contact, means for mounting said spring in proximity to said stub, said spring being in an arc around said fixed contact.

7. A sensitive mechanism for controlling an electrical circuit such as that of a sewing machine motor comprising a receptacle, a shaft pivoted within and on a wall thereof and having a pressure sensitive member secured thereon on the outside of said receptacle and adapted to contact with a thread under tension and to be moved thereby, an extension on said shaft in said receptacle, a stub shaft pivoted in said receptacle in proximity to the free end of said extension, a movable contact member secured to said stub, a projection on said movable contact cooperatively attached to the end of said extension, whereby oscillation of said shaft causes oscillation of said stub shaft and movable contact, a fixed contact in proximity to said movable contact and adapted to close a circuit therewith, and a spring one end of which is attached to said receptacle and the other end having an angular portion in said receptacle engaging the free end of said movable contact to maintain it in open and closed positions alternately, a base adapted to be secured to a machine head, said receptacle being mounted on said base.

75 8. A sensitive mechanism for controlling an

electrical circuit such as that of a sewing machine motor comprising a receptacle, a shaft pivoted within and on a wall thereof and having a pressure sensitive member secured thereon on the outside of said receptacle and adapted to contact with a thread under tension and to be moved thereby, an extension on said shaft in said receptacle, a stub shaft pivoted in said receptacle in proximity to the free end of said extension, a movable contact member secured to said stub, a projection on said movable contact cooperatively attached to the end of said extension, whereby oscillation of said shaft causes oscillation of said stub shaft and movable contact, a fixed contact in proximity to said movable contact and adapted to close a circuit therewith, and a spring one end of which is attached to said receptacle and the other end having an angular portion in said receptacle engaging the free end of said movable contact to maintain it in open and closed positions alternately, a base adapted to be secured to a machine head, said receptacle being mounted on said base a slide on said receptacle, said base having a groove in which said slide is mounted and a spring attached to said base and slide for vertical movement relative to said base.

9. A sensitive mechanism for controlling an electrical circuit such as that of a sewing machine motor comprising a receptacle, a shaft pivoted within and on a wall thereof and having a pressure sensitive member secured thereon on the outside of said receptacle and adapted to contact with a thread under tension and to be moved thereby, an extension on said shaft in said receptacle, a stub shaft pivoted in said receptacle in proximity to the free end of said extension, a movable contact member secured to said stub, a projection on said movable contact cooperatively attached to the end of said extension, whereby oscillation of said shaft causes oscillation of said stub shaft and movable contact, a fixed contact in proximity to said movable contact and adapted to close a circuit therewith, and a spring one end of which is attached to said receptacle and the other end having an angular portion in said receptacle engaging the free end of said movable contact to maintain it in open and closed positions alternately, a base adapted to be secured to a machine head, said receptacle being mounted on said base for vertical movement relative to said base, means for biasing said receptacle downwardly relative to said base and a stop for limiting the downward motion of said receptacle.

10. A sensitive mechanism for controlling an electrical circuit such as that of a sewing machine motor, said machine having a presser-foot, comprising a receptacle, a shaft pivoted within and on a wall thereof and having a pressure sensitive members secured thereon on the outside of said receptacle and adapted to contact with a thread under tension and to be moved thereby, an extension on said shaft in said receptacle, a stub shaft pivoted in said receptacle in proximity to the free end of said extension, a movable contact member secured to said stub, a projection on said movable contact cooperatively attached to the end of said extension, whereby oscillation of said shaft causes oscillation of said stub shaft and movable contact, a fixed contact in proximity to said movable contact and adapted to close a circuit therewith, and a spring one end of which is attached to said receptacle and the other end having an angular portion in

7
said receptacle engaging the free end of said movable contact to maintain it in open and closed positions alternately, a base adapted to be secured to a machine head, said receptacle being mounted on said base for vertical movement relative to said base, means for biasing said receptacle downwardly relative to said base and a stop for limiting the downward motion of said receptacle, and a finger fixed on said receptacle adapted to engage said presser-foot and to be lifted by the movement thereof.

11. A sensitive mechanism for controlling an electrical circuit such as that of a sewing machine motor comprising a receptacle, a shaft pivoted within and on a wall thereof and having a pressure sensitive member secured thereon, on the outside of said receptacle and adapted to contact with a thread under tension and to be moved thereby, an extension on said shaft in said receptacle, a stub shaft pivoted in said receptacle in proximity to the free end of said extension, a movable contact member secured to said stub, a projection on said movable contact cooperatively attached to the end of said extension, whereby oscillation of said shaft causes oscillation of said stub shaft and movable contact, a fixed contact in proximity to said movable contact and adapted to close a circuit therewith, and a spring one end of which is attached to said receptacle and the other end having an angular portion in said receptacle engaging the free end of said movable contact to maintain it in open and closed positions alternately, a base adapted to be secured to a machine head, said receptacle being mounted on said base for vertical movement relative to said base, and a tongue and groove arrangement on said receptacle and base adapted to provide said vertical movement.

12. A sensitive mechanism for controlling an electrical circuit such as that of a sewing machine motor comprising a receptacle, a shaft pivoted within and on a wall thereof and having a pressure sensitive member secured thereon on the outside of said receptacle and adapted to contact with a thread under tension and to be moved thereby, an extension on said shaft in said receptacle, a stub shaft pivoted in said receptacle in proximity to the free end of said extension, a movable contact member secured to said stub, a projection on said movable contact cooperatively attached to the end of said extension, whereby oscillation of said shaft causes oscillation of said stub shaft and movable contact, a fixed contact in proximity to said movable contact and adapted to close a circuit therewith, and a spring one end of which is attached to said receptacle and the other end having an angular portion in said receptacle engaging the free end of said movable contact to maintain it in open and closed positions alternately, a base adapted to be secured to a machine head, said base having recesses therein and a clamp adapted to embrace a part of said machine head, said receptacle being mounted on said base.
